B. AMES

1,836,832

COSMETIC COMPACT

Filed Sept. 24, 1929

UNITED STATES PATENT OFFICE

BUTLER AMES, OF LOWELL, MASSACHUSETTS

COSMETIC COMPACT

Application filed September 24, 1929. Serial No. 394,845.

This invention relates to toilet compacts and has for one of its objects the provision of a receptacle for holding and dispensing powder or rouge impregnated applicator pads of the type and claimed in the applicant's application of even filing date Serial No. 394,846.

Another object of the invention is to provide a toilet compact having an opening for the removal of the pads which is closed by one of the pads in such a manner as to prevent either powder or rouge from being wasted or smeared from the pads within the compact, or moisture from entering the compact.

Further objects of the invention are to retain the pads securely within the receptacle, and to permit them to be removed one at a time.

Another object of the invention is to provide a toilet compact adapted to contain a plurality of powder applicator pads and means for impregnating them with powder before use.

A further object of the invention is to provide a novel and efficient powder dispensing reservoir adapted to prevent waste and leakage of the powder.

Other objects of the invention are to provide a convenient location for the powder reservoir, and to provide a construction which facilitates the refilling of the reservoir and the replenishing of the supply of applicator pads.

In the drawings:

Fig. 1 is a plan view of a compact constructed according to the present invention;

Fig. 2 is a view similar to Fig. 1 but showing the cover of the compact completely opened;

Fig. 3 is a side view of the compact showing the cover partially opened;

Fig. 4 is a section on the line 4—4 of Fig. 1;

Fig. 5 is a section on the line 5—5 of Fig. 2;

Fig. 6 is a plan view, partly broken away, of one of the applicator pads adapted for use in the compact;

Fig. 7 is a section on line 7—7 of Fig. 6; and

Fig. 8 is a section similar to Fig. 7 but showing a modified form of applicator pad.

Referring to Fig. 4, the compact is provided with a circular metallic casing 11 having an annular inturned rim 12. Casing 11 is preferably plated with a metal which provides a reflecting surface, and the lower outer side of the casing may constitute a mirror which may be plane or convex. In the circular opening, defined by the annular rim 12, is detachably fitted the annular retaining member 14, which is secured to the rim 12 of the casing by the bayonet joint connections comprising the projections 15 on retaining member 14 and the notches 16 on rim 12.

Annular retaining member 14 is provided at its top with an inturned flange 17 which engages the top of a pile of pads 18 disposed within the casing and within annular retaining member 14. Each of the applicator pads 18 is separable from the pile. This result may be obtained by the use of some frangible connecting means for the pads or by providing a pile of separate non-attached pads as illustrated and described herewith. Each of these pads 18, shown in Figs. 6 and 7, consists of a circular piece 19 of suitable fabric material, for example, paper, cotton cloth, cotton batting, silk fabric, rayon, linen, soft woolen cloth or chamois, etc. This piece of material 19 is preferably impregnated or coated upon its upper surface with a cosmetic preparation, such as rouge or cold cream, indicated at 21. Over the top surface of the material 19 is placed a thin sheet 22 of an impervious protecting material which is preferably some flexible transparent substance, such as glassine or cellophane. The sheet 22 is affixed to the material 19 at a portion of its edge by suitable adhesive indicated at 22^a in Figs. 6 and 7.

It is, however, within the scope of the present invention to affix sheet 22 to the entire upper surface of the material 19, or to provide a sheet 22 which is unattached to the material 19, or in case no rouge or other cosmetic 21 is employed, to substitute an adhesive coating of impervious material, such as paint or nitro-cellulose lacquer applied to the upper side of material 19; or to eliminate the impervious protecting covering 22 entirely. If desired the pad 18 may be im-

pregnated on its under side 20 with powder.

In the modified form of applicator pad illustrated in Fig. 8, an upper covering of protecting material 22 is provided, as in the

5 form shown in Fig. 7, and also a similar covering of protecting material 28 on the lower side of the pad. These protective coverings may be affixed to the pad in any desired manner, but preferably by means of areas of adhesive 22^a and 28^a, applied as described

10 for the pad of Fig. 7. The pad of Fig. 8 is preferably coated with a cosmetic such as rouge at 21, and if desired may be impregnated with powder on the lower surface 20

15 of material 19. The two protecting coverings serve practically completely to enclose the applicator pad of this form of the invention and hence afford a maximum of protection against smearing or loss of the cosmetic or soiling of the fingers.

The pads 18 are described and claimed per se in my application of even filing date Serial No. 394,846.

At the bottom of the pile of pads 18 a 25 thin circular plate of metal 23 for engaging the bottom applicator pad and means for yieldingly forcing this plate toward the top of the casing are provided. The portion of the compact thus far described, together with 30 its filling of applicator pads, is described and claimed in my application of even filing date, Serial No. 394,844.

A continuous spiral wire spring 24 is provided adjacent and soldered at intervals to 35 the wall of the casing 11. One or more inwardly projecting arms 25, preferably three, are operatively connected to spring 24 and project through slots 26 in retaining member 14 to contact with the underside of plate 23 40 and yieldingly force the pile of pads 18 up against the inturned flange 17 of retaining member 14. A preferable and advantageous construction is shown in Fig. 4, wherein the inwardly projecting arms are formed of the 45 wire of spring 24 and constitute spirally twisted portions thereof. In place of the spring construction described above, springs associated with the plate 23, as described and illustrated in my copending application of 50 even filing date, Serial No. 394,844 referred to above, may be employed.

Each of the applicator pads 18, whether coated at 21 with rouge or other cosmetic or not, is, because of its soft flexible character, admirably adapted to serve as a conveyor for powder, rouge, or other facial cosmetic. A reservoir for holding and dispensing such cosmetic is incorporated in the structure of the compact, so that the whole 55 is self-contained and adapted to carry the necessary elements for make-up.

Referring to Figs. 1 and 2, a cap or cover 30 is connected by hinge 31 to the inwardly directed flange 17 of the retaining member 60 14 of the compact. Diametrically opposite

its hinge 31, the cover 30 is provided with a small hooked end clasp 32 (best seen in Fig. 5) adapted to pass through a notch 16 and engage the under side rim 12 of the casing for fastening cap 30 in a closed position. Cover 30 is also preferably plated with a metal which provides a reflecting surface, and the outer side of the cover may constitute a mirror which may be plane or convex.

70 While in the form of toilet compact illustrated and described herein, the cap 30 is hinged to the annular retaining member 14, it is within the scope of my invention to hinge cap 30 directly to the casing 11, or in any other manner that will provide a hinged cosmetic dispensing member associated with the casing.

75 Referring to Fig. 5, cap 30 is cup shaped in cross section, having a depressed bottom portion surrounded by side walls. Within the depression in cap 30 is provided an annular plate 33 which constitutes a means for confining cosmetic within the cover. Plate 33 is curved in section and is shown in Fig. 5 as 80 inwardly and downwardly inclined toward the center of the depression of cover 30.

85 Referring to Figs. 2, 4 and 5, portions 34 of plate 33 extend into contact with cover 30, but intermediate cut away portions are 90 provided to form outlets 35 for powder to pass between plate 33 and cover 30 into the open central portion 36 of the cover. The annular space 37 between plate 33 and the cover 30 is adapted to hold a quantity of 100 cosmetic sufficient for a number of applications. It is contemplated that, for example, pulverized powder or facial "powder" in a cake form may constitute the cosmetic carried by the reservoir.

105 In using the compact, the top one of the pads 18 is frictionally pushed with the thumb or finger to distort it sufficiently to permit it to pass through the annular flange 17 and thereby be removed from the compact. The 110 pad 18 is then rubbed or brushed over the central portion 36 of the cover, and sufficient cosmetic, for example powder, passes through the outlets 35 from the reservoir 37 to impregnate the applicator pad to the desired 115 extent. The pad may then be used to apply the cosmetic to the face, after or before which the flexible protecting covering 21 may be turned back to expose the rouge or other cosmetic 20 on the upper side of the pad. It is thus apparent that the compact of the 120 present invention provides the essentials for make-up within a single compact. If facial "powder" in a cake form is carried in the 125 reservoir, the pressure of the applicator pad on the plate 33, and the slight movement of plate 33 caused by a rotary brushing motion of an applicator pad, will assist in causing the cake to crumble and allow granular 130

powder to flow out into central portion 36 where it is accessible to the applicator pad.

By slightly rotating the annular member 14 and its hinged cover 30 with respect to the casing 11 of the compact, the bayonet joints, consisting of projections 15 and notches 16, may be unfastened, and the annular retaining member 14 and hinged cover 30 readily lifted from and detached from the remainder of the compact. Cover 30 constitutes a convenient handle for rotating member 14 to remove it from the casing and likewise to restore it to its locked position with respect to the casing. By disengaging retaining member 14 from the casing 11, additional applicator pads 18 may be supplied to the compact, and by removing plate 33 from the depressed cover portion an additional supply of powder may be added to the reservoir 37.

20 While the toilet compact illustrated in the accompanying drawings is circular in shape, other shapes of casings and pads, such as square, octagonal, oval, etc. may be utilized.

I claim:

25 1. A toilet compact comprising a pile of substantially flat separable applicator pads, a casing substantially surrounding said pile of pads on all sides except the top, retaining means for said pads and a spiral spring provided with an inturned arm for yieldingly forcing the pile of pads against said retaining means.

30 2. A receptacle for holding an applicator pad, comprising a casing, a spring disposed within said casing adjacent the wall thereof, and an inwardly extending arm on said spring adapted to press the pad toward the top of the compact.

35 3. A receptacle for holding an applicator pad, comprising a casing, a spring disposed within said casing adjacent the wall thereof, and an inwardly extending arm on said spring adapted to press the pad toward the top of the compact, said inwardly extending arm being formed of the wire of said spring.

40 4. A receptacle for holding an applicator pad, comprising a casing, a spring disposed within said casing adjacent the wall thereof, and an inwardly extending arm on said spring adapted to press the pad toward the top of the compact, said inwardly extending arm comprising a spirally twisted portion of the wire of said spring.

45 5. In a receptacle for holding an applicator pad, comprising a casing, a member depending within said casing and provided with retaining means for retaining a pad within said casing, and a spring actuated arm within said casing passing through a slot in said annular member for pressing the pad against said retaining means.

Signed by me at Boston, Massachusetts
this 14th day of August, 1929.

BUTLER AMES.
